United States Patent Office

Des. 179,540

Patented Jan. 15, 1957

179,540

MICROPHONE STAND

Josef S. Knechtsberger, Chicago, Ill., assignor to Shure Brothers, Incorporated, Chicago, Ill., a corporation of Illinois

Application April 27, 1954, Serial No. 30,216

Term of patent 14 years

(Cl. D26—14)

Fig. 1 is a perspective view of a microphone stand embodying my new design;

Fig. 2 is a side elevational view thereof to an enlarged scale; and

Fig. 3 is a top plan view thereof to an enlarged scale.

The features of my design reside in those portions shown in full lines, the dotted line showing being for illustrative purposes only.

I claim:

The ornamental design for a microphone stand, substantially as shown and described.
